UNITED STATES PATENT OFFICE.

THEODORE MAYNARD, OF BELLINGHAM, WASHINGTON.

PRESERVE-JAR.

1,097,180.

Specification of Letters Patent.

Patented May 19, 1914.

Application filed May 23, 1913. Serial No. 769,530.

To all whom it may concern:

Be it known that I, THEODORE MAYNARD, a citizen of the United States, residing at Bellingham, in the county of Whatcom and 5 State of Washington, have invented certain new and useful Improvements in Preserve-Jars, of which the following is a specification.

This invention relates to an improvement 10 upon that class of receptacles for preserves illustrated in the patent granted to David E. Lain and myself October 11, 1910, No. 972,206.

The chief objects of the invention are to 15 insure expulsion of all air from the jar in the act of sealing, to provide more effective sealing means and to locate the clamping device so that it will be largely protected by the cover which it holds to the jar.

20 The invention therefore consists in the structure of parts and in their combination, for the purpose specified, substantially as herein set forth and claimed.

In the accompanying drawing, which 25 forms a part of this specification, Figure 1 represents, in vertical axial section, the upper portion of one of the improved preserve jars showing the cover as clamped to the receptacle and completely sealed thereon; Fig. 2 is a partially sectionized elevation of the same structure showing the clamping lever raised as before applying pressure to the parts in sealing; and Fig. 3 is a plan of the structure as shown in Fig. 1.

35 The receptacle indicated at 5 and cover at 6 may be of any suitable material, preferably glass. The form preferred for the receptacle is that wherein the vertical elements of the interior wall are uninterrupted, 40 the exterior wall having a shoulder or bead extending around the top to secure the re-entrant ends of the clamp 7.

The improved cover 6 has its central portion depressed so that the upper surface of 45 said depression will be below the upper edge of the receptacle. This depression extends well toward the edge of the cover and so forms an inner shoulder for centering the cover upon the receptacle and for holding the gasket 8 in place on the cover ready 50 for application of both together to the receptacle. To make sure of the peripheral seal by gasket 8 two annular beads or ribs 9 are formed on the cover to be pressed into 55 the gasket when the clamp is applied. The chief purpose served, however, by depressing

the central portion of the cover, is that of absolutely insuring the expulsion of the last bit of air from the jar through the central aperture 10 in applying the cover to the jar. 60 As will be readily seen this result must follow if the receptacle is filled practically level full. The issuance of the air bubbles is somewhat assisted by slightly concaving the under surface of the cover at the center 65 thus leading the air to the hole 10. The form of clamp shown is especially well adapted for use on this improved cover with its means for final central sealing, which is effected by holding down a disk 11, of rubber or other suitable material, over the hole 70 10, at least until the contents of the jar have cooled when atmospheric pressure will continue the seal of said disk. The said disk is held down and the cover clamped to the 75 jar by depressing the cam lever 12, which is pivoted in a central aperture in clamp 7. To prevent displacement of disk 11 by the shoving action of the cam-end of said lever, a thin metal strip 13 is attached at one end 80 to the underside of clamp 7 and has its free end interposed between said cam and the disk. It is desirable that this strip 13 follow the said cam when the lever is thrown up, thereby to more readily permit the application or adjustment of the disk 11 after 85 the clamp has been applied. This purpose is accomplished by making said strip from spring metal. It is also essential that nothing shall interfere with the proper tightening of the strip 13 upon the disk 11, therefore the retaining bead 14, for the disk 11, is diametrically divided and the clamp preferably placed so that said strip will be aligned with the openings between the parts 90 of said bead, as seen in Fig. 3. These gaps in the annular bead 14 also permit the ready escape of the liquor discharged through aperture 10 following the discharge of air through said aperture on the application of the cover to the jar. 95

From the above description, it is obvious that with the receptacle filled practically full, the cover, when applied, will, because of its center being depressed, displace all 100 the air trapped between the cover and the surface of the contents of the jar, which air will flow out through hole 10. Some liquid will also find outlet through said hole, so that upon application of the sealing disk 110 11 no air remains in the jar. Then by turning down the lever 12, the cover is

tightened upon its gasket and the disk upon its hole, thereby effecting a complete sealing of the jar.

The invention claimed is:—

- 5 In a preserve jar, the combination with the receptacle, of a centrally perforated cover provided with peripheral sealing means and having its entire central portion, within the receptacle, depressed to a depth 10 such that the upper surface of the depression is below the upper edge of the receptacle for the purpose specified, a sealing disk for said central perforation, a diametrically divided bead concentric with said hole for 15 retaining said disk, a clamp whereby the disk may be tightened upon the cover and the cover upon the receptacle and having

a cam lever for effecting said tightening, and a spring-metal strip attached to said clamp by one end and adapted to follow 20 the cam of said lever from one position to the other for the purpose specified and to be interposed between said cam and the disk and in alinement with the gaps in said bead when said lever is turned down into sealing 25 position all substantially as and for the purpose set forth.

In testimony whereof I affix my signature in presence of two witnesses.

THEODORE MAYNARD.
